VENTILATING SYSTEM FOR SUBMARINES

William F. Sheffield, Sparrows Point, Md.

Application May 20, 1942, Serial No. 443,723

1 Claim. (Cl. 114—16)

This invention refers to submarines and more particularly to systems for the ventilation and removal of foul gases therein and the air modification of the occupied sections of the vessel. It has among its objects to provide arrangements for air-conditioning the vessel and exhausting the used air therefrom when submerged, against the pressure of the surrounding waters. Another object is to connect the exhaust gases of the engines to outlets external to the vessel and through equipment that will enable them to pass out into the waters and exhaust freely therein, when the vessel is submerged. A further object is to have the system arranged so that the use of chemicals to change the condition of the atmosphere within the vessel will not be essential. A still further object is to have the atmospheric air together with the gases exhausted from the internal combustion engines used in the submarines, combined in a single system and forced out of the vessel together through a screw threaded mechanism designed to facilitate their propulsion through the waters under pressure and their mixture therein, to make the bubbles resulting therefrom relatively inconspicuous.

Other objects will become apparent as the invention is more fully set forth.

The atmospheric conditions within a submerged submarine are a source of considerable inconvenience and danger to the occupants due to their vitiation as the result of breathing and mixture with various products used within the chambers of the vessel. The engines are usually of the internal combustion type and develop gases in their exhaust that are very poisonous and dangerous. There has been great difficulty, up to the present, in getting rid of same while the engines are running during the submergence of the vessel. In fact it is considered impractical to run same and propel the vessel under water at the same time. This invention is intended to overcome these difficulties and greatly increase the efficiency of the vessel, as well as increase the safety and convenience of its occupants. This is done by providing an arrangement for air-conditioning the interior chambers of the vessel while submerged and removing the exhaust gases from the engines by forcing them to dissipate through the waters at a pressure greater than that of the water, through which the submarine is travelling. Further details of the construction and operation of these arrangements are indicated in the drawings and the following description, outlining an example of a submarine having such arrangements provided therein.

In the drawings, which illustrate an embodiment of this invention:

Figure 1 is a longitudinal sectional view through a submarine having an air-conditioning and exhausting system embodying this invention indicated herein.

Figure 2 is a transverse sectional view through the submarine along line 2—2 of Figure 1.

Figure 3 is an enlarged longitudinal sectional detail of the exhausting and gas removing outlet used in the air-conditioning system lines, for removing the expended gases under a pressure greater than that of the surrounding water in which the submarine is submerged in.

Figure 4 is a longitudinal sectional view through a submarine showing a modified arrangement of the exhausting and air-conditioning system outlined in this invention.

Figure 5 is a transverse sectional view through the submarine taken along line 5—5 of Figure 4, and

Figure 6 is an enlarged longitudinal sectional detail of the exhausting and gas removing outlet used in the air-conditioning system, showing the exhausting pumping means directly connected to the main drive shaft.

Similar reference characters refer to similar parts throughout the drawings.

In the construction indicated, 1 represents the hull structure of a conventional submarine with a propellor 42 and with partitions that divide it up into the usual rooms used by the personnel and occupied by the various types of equipment used therein. The equipment 4 indicates internal combustion engines used for propelling the vessel and 5 the line of exhaust pipes leading therefrom. A system of ducts 6 with valves 8 and register outlets 7 serves to inject clean air under slight pressure into the various rooms, to mix with the atmosphere therein and keep it normal. This duct piping connects with a tank 9 which is suitably attached to the framework of the submarine and has facilities 10 for controlling the pressure of air into it. A removable compressed air cylinder 11 is attached thereto. This air cylinder enables new air 2 to be supplied to the duct piping and distributed through the outlets 7 to mix with the air in the room and dilute the noxious vapors therein. Another system of duct piping 31 is preferably attached to the upper portion of the submarine framework for conducting the noxious vapors and used air 3 from the rooms. The piping 31 has valves 12 and registers 13 for assisting in this work and removing the air at designated locations.

Pumps 14 connect with the duct piping 31 and remove the air coming into them, and discharges it under pressure into a reservoir 15 where it accumulates until removed by a pressure booster pump 16, through connection 32, valve 33 and forced through the remainder of the system 26, check valve 35 thence through the helical or screw-like mechanism 17 mounted in a cylindrical casing 34. The latter terminates in an outlet 18 that projects through the wall of the submarine for discharge into the sea. The duct piping has check valves 19 and other suitable devices to prevent the return of exhausted gases into the piping or the entrance of the outside water under pressure.

The internal combustion engines 4 exhaust their gases into the pipe line 5, which in turn connects with the muffler 41, pipe 36, check valve 19 through pump 14 which exhausts the gas into the gas reservoir 25 under pressure. From the reservoir 25 the exhaust gases pass through valve 126 and incidental piping 127, pump 16 and helical mechanism 17. The pump 16 and helical mechanism 17 are driven by motor 37 and chain 38. The check valves 19 and 35 are provided to prevent any return of the gases or the admission of the pressure waters into the engine system. The motor 37 and chain 38 may be eliminated and pump 39 placed directly on the shaft 40, inside of housing 41.

In the operation of the system, the air cylinder 11 and regulating valve 10 are opened and allows the air 2 to flow into the ducts 6 and through stop valve 8 through the registers 7 and into the submarine. The register outlets are preferably directed towards the floor. The air 3 is removed from the ceiling by registers 13 and conveyed through valves 12 into ducts 31 by the compressing air pumps 14 which convey it to the storage tank 15 under pressure. The pump 16 takes the air and gases from the air or gas stor-

age compartments 15 or 25 and discharges them into the helical mechanism 17 from which they are exhausted into the sea at sufficient pressure to overcome the resistance offered, this is accomplished through the assistance of the helical screw device in driving out the water as it seeps into the cylindrical casing.

The check valves prevent any return gases or water from backing into the ducts. When the air cylinder 11 is empty, it is replaced by another and thus keeps the rooms supplied with new air. The air cylinders may be restored with air, when the submarine is running above the surface by using the pumps to compress same therefore. The helical mechanism serves to mix the exhaust gases and water together as it passes therethrough and distribute same into the seas in a uniform and comminuted form that makes them less conspicuous on the surface of the seas and lessens the burden on the pumps.

While but one general form of the invention is shown in the drawings, it is not desired to limit this application to this particular form or in any other way otherwise than limited by the scope thereof, as it is appreciated that other forms could be made that would use the same principles and come within the scope of the appended claim.

Having thus described the invention what is claimed is:

30 In a system of the class described for submarines, a helical mechanism operating within a cylinder in a rotative manner and arranged to project material in a predetermined direction, and duct means connecting the cylinder and helical mechanism with the atmosphere in the submarine for exhausting same, means for operating the said mechanism and means for keeping the air within the duct means under pressure while the mechanism is operating.

WILLIAM F. SHEFFIELD.
